TAP FOR LIQUID RECEPTACLES

Victor Alvear, Brooklyn, N. Y., assignor of one-half to Eddilaw Young, Long Island City, N. Y.

Application January 21, 1935, Serial No. 2,720

6 Claims. (Cl. 217—111)

This invention relates to taps for receptacles for liquids and more particularly to taps for barrels for holding beer and other beverages.

The main object of the invention is to provide a device of the above types embodying a separate closure member for the outlets of liquid receptacles which is of novel form and more convenient and economical than those commonly used. Another object is to provide a closure for such outlets which contains a breakable and removable element of new form and mode of application. A further object is to provide improved means for connecting the closure member with the draw off apparatus. Still another object is to provide a device of this class in which the breakable element is ruptured by means separate from the draw off pipe or rod.

The embodiment of my invention which I prefer to employ containing the above improvements, together with other advantageous and novel features of my invention which will be hereinafter more fully described, is illustrated in the drawings accompanying and forming part of this specification, and in which,—

Figure 1 is a central vertical section partly in elevation of one form of my improved tap for liquid receptacles.

Fig. 2 is a plan of the closure member or ring for the same.

Fig. 3 is an enlarged vertical section of a sealing member for use with my invention.

Fig. 4 is a top plan of the same.

Fig. 5 is a bottom plan of the same.

Fig. 6 is a side elevation of a tool for setting the sealing member.

Fig. 7 is a central vertical section partly in elevation of another form of my invention.

Fig. 8 is a plan of the closure member or ring for the same.

Fig. 9 is an enlarged vertical section of a sealing member for use with the same.

Fig. 10 is a top plan of the sealing member, and

Fig. 11 is a bottom plan of the same.

Referring to Fig. 1 of the drawings, the numeral 2 indicates the wall of a liquid receptacle such as for instance the head of a barrel, and 3 is the outlet opening of the same. There is a closure member such as the ring 5 which is preferably screw threaded at 6 to engage a companion screw thread 4 in the opening 3. Preferably there is a flange 7 on the ring 5 and there is a beveled part 8 on the lower side thereof and both of said parts are adapted to fit a recess 9 formed 55 in the wall 2.

The closure member or ring 5 is of nonrusting material and is provided with a bore 10 which bore has a reduced part indicated by 11 and a further reduced part 12. In said part 11 is placed a suitable member such as the nipple 13 which is preferably of harder material than the ring 5 and also nonrusting. It is preferably held in said bore by placing it in position by what is ordinarily termed a forced fit so that it is securely held in the ring 5 and practically forms a part 10 thereof. The nipple 13 preferably has a screw threaded outer part 14 and a bore such as 15 having a reduced portion 16. Between the main portion of the bore 15 and the portion 16 is a shoulder 17 and in the lower part of the main portion 15 is a recess 18 preferably tapered as at 19 from the outer part inwardly and ending in a beveled groove 20, the bevel of which is joined to the shoulder 17.

In the recess 18 of the nipple 13 is placed an annular sealing member such as 23, which consists of a portion 24 to cover the shoulder 17 of the nipple 13, a portion 25 to cover the reduced portion 16 of the bore 15, and a peripheral portion 26 preferably tapered upwardly or outwardly as shown and by means of which it is adapted to be held in the recess 18. When finally set in sealing position it has an upset bead or rim 27 which fits the groove 20. There is an annular element 28 of flexible material such as paper affixed to the bottom or inner side of the member 23 which is adapted to make the seal watertight.

There is a connection member or fitting 33 adapted to be placed over and secured to the member 5. Preferably there are coupling means 35 such as the coupling sleeve 34 mounted on the connection member 33 and preferably turnable thereon. The said sleeve 34 has an internal screw thread 35 to engage the external screw thread 14 of the nipple 13 and also has thumb pieces 36 by which it can be turned. The sleeve 34 has a bore 37 and a reduced part 38 of the sleeve fits the outside of a short tube 39, screw threaded at 40 to secure it to the connection member 33 and also having a collar 41 to bear against the shoulder 42 of the sleeve 34 to hold it turnably on the tube 39. Inside of the tube 39 is a tubular cutter 43 having a sharpened lower edge 44, said cutter being securely fastened to said tube 39 and movable therewith 50 and with the connection member 33. There are holes 45 for turning the tube 39 into and out of place. There is a collar 46 of rubber or similar material secured around the lower part of the cutter 43 and adapted to press against the 55

top or outer part of the sealing member 23, to hold the same more firmly when it is being perforated by the cutter 43.

The connection member 33 has a branch 48 which can be attached to a compressed air pipe such as the pipe 49. At the outer part of the member 33 is a stuffing box such as 50 having a screw threaded gland 51 and a packing 52.

The closure ring 5 having been inserted in the wall 2 of the receptacle, the latter is filled with the desired liquid and the sealing member 23 is placed in the nipple 13 in the shape shown in the dotted line position in Fig. 6. It is then secured in position in any suitable manner such as by driving it home by a suitable implement such as that shown for instance in Fig. 6. The implement shown in said figure has a shank a, a head b, and a nose c having a rim or bead d conforming in shape to the groove 20 of the nipple 13. This implement having been brought down against the member 18, is given a blow with a hammer or suitable tool and sets the sealing member 23 firmly in the recess 18 by expanding the peripheral portion 26 outward into the same. It is moved downwardly as well so that its upper edge 26' passes below the upper edge of the recess 18 and expanding outwardly is firmly caught under the same. The portion 26 is made a close fit in the bore 14 and thus a very slight expansion in its diameter is sufficient to hold it firmly in the recess 18.

When it is desired to remove the contents of the receptacle, the connection member or fitting 33 is secured to the closure member 5 by coupling it to the screw threaded part of the nipple 13 thereof by means of the coupling sleeve 34. When the sleeve 34 is nearly at final downward position, the tubular cutter 43 will contact with the top part of the sealing member 23. Further movement of sleeve 34 will cause the cutter 43 to cut through the member 23 so that the contents of the receptacle can flow into the draw tube 54 through the member 33 and thence into suitable receptacles. The draw tube or rod 54 passes through the stuffing box 50 thus preventing spilling of liquid when pressure of air is brought into the receptacle on connection of the member 33 with the air pipe 49.

The sealing member 23 is preferably formed with a weakened portion such as 55 which will more readily and surely give way to the cutter 43. The said portion 55 is annular and defined by the circular scoring 56 and is in fact almost broken through the sheet metal of which the member 23 is formed. The scoring is not a complete circle however but there is a narrow part 57 which is not scored. The said member 23 is further depressed inward at 58 toward the interior of the receptacle, so as to more readily give way and preferably there are indentations 58', ordinarily three in number which also assist to weaken this part to give way to the cutter 43. Thus the part 55 will be more sure to move out of the opening in the member 23 but will hang by the portion 57 and the opening in said member will be practically clear to permit the passage of the contents of the receptacle into the connection member 33. When it is desired to remove the broken sealing member 23, this can be effected by a suitable implement such as a screw driver or the like through the slots 29 in the nipple 13.

In the form of the device shown in Fig. 7 the numeral 2' indicates the wall of a liquid receptacle and 3' is the outlet opening of the same.

There is a closure member such as the ring 5' screw threaded at 6' to engage the screw thread 4' of the opening 3'. The closure member 5' has a bore 60 which is internally screw threaded at 61 and said member also has a reduced part 62 of the bore indicated by 62. In said part is placed a suitable member such as the nipple 63 and the latter is held in the bore by a forced fit. The nipple 63 preferably has a collar 64 which rests on the shoulder 65 of the member 5'. There is a beaded part 66 of said nipple at its outer end and there is also a bore 67 through the nipple which bore is ordinarily tapered. The said nipple 63 is of nonrusting material and the part 66 is hardened.

On the beaded part 66 of the nipple 63 a sealing member such as 68 is adapted to be placed, and it consists of a portion 69 to cover the end of the bore 67 of the nipple 63 and a peripheral portion 71 preferably turned inwardly as shown and by means of which it is adapted to be held on the side 72 of the beaded part 66. The portion 71 is preferably made with corrugations such as 73 by means of which it can be crimped tightly onto the part 66. There is an annular part 74 inward of the portions 69 and 70 preferably made of flexible material such as paper.

On the inner side of the member 5' I have placed another closure member such as the check valve 76 which may be of any suitable form but preferably has a disk 77, a pivot support 78, a pivotal portion 79, a pivot 80 and a counterweight such as 81.

There is a connection member or fitting 33' adapted to be placed over and secured to the member 5'. Preferably there are coupling means such as the sleeve 34' mounted on the connection member 33' and preferably turnable thereon. The said sleeve has an external screw thread 35' to engage the internal screw thread 61 of the member 5' and thumb pieces 36' by which it can be turned. In other respects the connection member 33' is like the similar connection member 33 of Fig. 1, and including a tube 39' to hold the sleeve 34' turnably on the member 33', the cutter 43' secured in member 33' and the yieldable collar 46' to press on the sealing member 68 when the same is being ruptured. The sealing member 68 has scoring 56' and indentations 58'' defining inwardly depressed part 58''''. It also has the part 57' corresponding to 57 in Fig. 4 and 69 refers particularly to the part over the seat on nipple 63.

The check valve 76 may be used with the sealing member of either form of the tap and when it is used the draw tube 54 or 54' must be pushed down through the stuffing box 50 or 50' after the sealing member is broken through, so as to open up the check valve and permit passage of liquid. This also has to be done if for any reason the check valve is used without the sealing member.

What I claim is:—

1. A tap for liquid receptacles comprising an outer annular member, an inner annular member, each of said members provided with a bore, the inner member secured in the bore of the outer member, the inner member having a hardened seat, means for attachment of a draw off device, and a sealing member having a bottom part provided with an inner pre-defined breakable portion, a sealing portion surrounding the same, and a peripheral flange without the sealing portion and whereby it is held on said seat of the inner annular member.

2. A tap for liquid receptacles comprising an outer annular member having means for attach-

ment to the outlet opening of a liquid receptacle, an inner annular member, each of said members provided with a bore, the inner annular member secured in the bore of the outer member and having a hardened seat, there being an annular space at the outer part between said members, means adjacent said annular space for attachment of a draw off device, and a sealing member having a breakable portion, a sealing portion surrounding the same, and a peripheral flange without the sealing portion and whereby it is held on said seat of the inner annular member.

3. A tap for liquid receptacles comprising an outer annular member having means for attachment to the outlet opening of a liquid receptacle, an inner annular member, each of said members provided with a bore, the inner member secured in the bore of the outer member and having a hardened seat, there being an annular space at the outer part between said members, screw-threaded means adjacent said space for attachment of a draw off device, and a sealing member having a breakable portion, a sealing portion surrounding the same, and a peripheral flange without the sealing portion and whereby it is held on said seat of said inner annular member.

4. A sealing member for a tap for liquid receptacles embodying a member having an upright annular flange and a bottom portion joined thereto provided with a pre-defined breakable portion and an annular beveled bottom element extending downwardly and outwardly toward the periphery to fit an outwardly beveled seat and surrounding

the breakable portion which beveled element on being forced downward by means bearing only on itself causes said flange to expand outwardly into a groove placed adjacent to it.

5. A tap for liquid receptacles comprising an annular outer member having means for attachment to the outlet opening of a liquid receptacle, an inner annular member, each of said members having a bore, there being a shoulder in the inner part of the outer member, said inner member secured in the bore of said outer member against said shoulder and also having a hardened seat beveled outwardly from the periphery, a sealing member having a bottom part buckled outwardly to fit said seat, a breakable portion surrounded by said buckled portion and a separate peripheral flange whereby it is held on the seat of said inner annular member, and means for attachment of a draw off device.

6. A tap for liquid receptacles comprising an annular body portion having means for attachment to the wall of a receptacle, said tap having an internal shoulder and a seat therein beveled inwardly toward its periphery, a holding edge outward of the seat and a groove of greater diameter between them, a sealing member having a bottom portion whose outer part lies on and fits said seat and a flange expanded into said groove and its outer edge engaged with said holding edge outward of the seat, and means for attachment of a draw off device.

VICTOR ALVEAR.
